HYDRAULIC PRESS

Francis B. Fishburne, Asheville, N. C.

Application July 16, 1946, Serial No. 683,955

13 Claims. (Cl. 100—71)

1

This invention relates to hydraulic presses, and more particularly to that type of press employing an accumulator in which pressure is built up by means of a pump.

Hydraulic presses as heretofore constructed have usually embodied a massive cast iron frame of sufficient weight and strength to withstand the strains to which it is subjected. Such apparatus has therefore not only been excessively heavy, but also relatively expensive to produce.

One of the objects of the present invention therefore is to design a press frame which may be readily fabricated from steel plates, by means of welding, and which, while possessing the necessary strength, will be both light in weight and relatively inexpensive to manufacture.

Furthermore, in hydraulic presses of the accumulator type as heretofore constructed, it has been the common practice to provide accumulator tanks or the like separate from and in addition to the press itself, thus requiring a large amount of floor space. Another object of the present invention is to provide a hollow press frame having the necessary accumulator structure enclosed within the same, so that the apparatus is self-contained and compact and occupies but relatively little floor space.

In order to render the apparatus still more compact, and to still further conserve floor space, the invention contemplates mounting the pump and control mechanism also wholly within the hollow press frame. In addition, my improved press frame contains a chamber constituting the liquid reservoir from which liquid is pumped into the accumulators. Thus, with my improved construction, the entire press and all of its accessories constitute but a complete unit, no outside apparatus whatsoever being required.

In order that the invention may be clearly understood, reference is had, by way of illustration, to the accompanying drawings, forming part of this specification, and in which—

Fig. 1 is a front elevation of the complete press, parts being broken away.

Fig. 2 is a side elevation thereof.

Fig. 3 is a rear elevation thereof.

Figs. 4, 5 and 6 are views similar to Figs. 1, 2 and 3, but showing only the frame of the press stripped of all mechanism.

Fig. 7 is a plan view of the frame as shown in Fig. 5.

Fig. 8 is a transverse section substantially on the line 8—8 of Fig. 5 looking in the direction of the arrows.

Fig. 9 is a transverse section substantially on

2

the line 9—9 of Fig. 5 looking in the direction of the arrows.

Fig. 10 is a side elevation of the accumulator structure itself, and associated parts, detached from the press frame, parts being in section.

Fig. 11 is a similar view taken at right angles to Fig. 10.

Figs. 12 and 13 are sections, respectively, on the lines 12—12 and 13—13 of Fig. 10 looking in the directions of the arrows.

Fig. 14 is a diagrammatic view illustrating a simple hydraulic system which may be employed.

Fig. 15 is a horizontal fragmentary section on a somewhat enlarged scale, taken substantially on the line 15—15 of Fig. 2 looking in the direction of the arrows.

Fig. 16 is a vertical longitudinal section through the upper part of my improved press frame, parts being broken away and parts being shown in dotted lines.

Fig. 17 is a horizontal section substantially on the line 17—17 of Fig. 16 looking in the direction of the arrows, the parts shown in dotted lines in Fig. 16 being omitted for the sake of clearness; and

Fig. 18 is a transverse section on the line 18—18 of Fig. 17 looking in the direction of the arrows.

Referring to the drawings in detail, I have illustrated in Figs. 1 to 3 a press frame of what is known as the gap type, that is to say an arrangement in which the upper and lower parts of the frame extend beyond the middle portion and support a platen and power cylinder in opposed relation.

My improved press frame is hollow and is fabricated from steel plates secured together along their edges as by means of acetylene or electric arc welding. The frame comprises a bottom plate 1, suitably shaped side plates 2 and 3 and a rear plate 4. This produces a rectangular structure such as shown in Figs. 7, 8 and 9.

The front portion of the press frame adjacent the power cylinder is also provided with a top plate 5, and the lower portion of the frame adjacent the platen is provided with a front plate 6. The latter is perhaps most clearly shown in Fig. 9. Referring to this figure, it will be seen that adjacent the rear side of the platen, the side plates 2 and 3 are tied together by a transverse plate 1, welded thereto. The platen itself, which is designated 15, is of somewhat greater width than the distance between the side plates 2 and 3, and projects beyond the same. These projecting ends of the platen are supported by auxiliary plates 10 and 11 parallel with the side plates and

3

welded at their front edges to the plate 6 and at their rear edges to filler plates 8 and 9.

Adjacent the rear edge of the press frame are pedestals 2a and 3a, and adjacent the plates 8 and 9 are pedestals 8a and 9a, these pedestals having openings by means of which the press may be bolted to a suitable foundation.

Referring again to Fig. 9, it will be seen that between the plates 6 and 7 and the side plates 2 and 3 I provide additional vertical supporting plates 12 and 13, welded to the plates 6 and 7. It will thus be understood that all of the plates 2, 3, 6, 7, 10, 11, 12 and 13 cooperate in effectively supporting the platen 15, so that this platen may readily withstand all of the strains imposed upon it.

Referring to Figs. 1, 2, 4 and 5, it will be seen that the gap in the press frame between the power cylinder and platen is formed by a curved plate 14 bent to the desired shape and welded to the side plates 2 and 3.

The space between the side plates in which the power cylinder is mounted, as hereinafter described, is closed by a cover consisting of a front plate 16 and side plates 16a, held in place by cap screws 17, passing through the latter.

A horizontal partition 18 extends across the upper part of the press frame as shown in dotted lines in Fig. 5 and in full lines in Figs. 4 and 17, and constitutes a floor for supporting the pump and control mechanism hereinafter more particularly described. In order to afford access to this pump compartment formed by the partition 18, the top, side and end plates are divided along the line 19a in Figs. 2 and 5 to form a removable cover 19.

Referring now particularly to Figs. 16 to 18, the power cylinder is indicated at 20, and this is supported by means of a specially designed adapter. This adapter comprises a transverse plate 21 and a pair of extra heavy side plates 22, welded together, and the plates 22 fit snugly against the side plates 2 and 3 and are welded thereto. The opposite sides of the cylinder 20 are formed with flat carefully machined faces which fit against the inner faces of the plates 22, and the cylinder is secured in position by means of large cap screws 23 which pass through the plates 2, 3 and 22 and into the relatively thick walls of the cylinder. The cap screws 17, heretofore referred to, also engage the plates 22.

The front edges of the top plate 5 and curved plate 14 are made of arcuate shape, as indicated at 5a and 14a respectively, to fit around and embrace the power cylinder 20.

As stated in the preamble, one of the important features of the present design resides in the fact that an accumulator structure is built into the hollow press frame. This accumulator structure preferably comprises one or more tubular or cylindrical containers 24, two such containers being shown. They extend from the bottom plate 1 to the partition 18 and are disposed one behind the other transversely of the press frame in such a manner that they substantially fill the space between the side plates 2 and 3 as best shown in Figs. 8 and 9. At their forward side, the space between the tubular members 24 is bridged by a filler strip or plate 25 welded thereto. Also, at the lower part of the frame, I provide a pair of vertical brace plates 26 welded at their forward edges to the transverse plate 7, and at their rear edges to the tubular containers 24. Similar brace plates 26' extend between the upper part of the

4

cylinders 24 and the plate 21 of the adapter above described, as shown in Fig. 8.

At the rear side of the cylinders 24 the spaces between them and between each of them and the adjacent side plate are bridged by filler strips or plates 27, 28 and 29, these strips or plates being welded to the cylinders and to the side plates, as clearly shown in Figs. 8 and 9. Thus, the cylinders are anchored or tied to each other and to the side plates by welding.

It will thus be seen that by virtue of the various longitudinal and transverse plates, combined as described with the pair of vertical tubular members 24, an exceedingly strong and rigid fabricated structure is produced, the tubular members 24 serving not only as an accumulator structure but also as an important part of the press frame itself, serving to effectively reinforce and strengthen this frame.

Furthermore, the filler strips 27, 28 and 29 serve to effectively seal off the rear portion of the interior of the press frame to form a chamber 35, of which the accumulator structure forms one wall. I utilize this chamber as a reservoir for the liquid employed to operate the press. Access to this reservoir is afforded by manholes 4a and 4b, closed by covers 4c and 4d, as shown in Figs. 3 and 6.

Adjacent one corner of this chamber I place an angle iron 30 which is welded at one edge to one of the tubular containers 24, and at the other edge to the side plate 3. This angle iron forms a vertical passageway, sealed off from the liquid in the chamber 35.

Adjacent and forward of this passageway is a short section of pipe extending horizontally and transversely through the container 24, as indicated at 31 in Figs. 9, 10 and 13, this piece of pipe constituting a tunnel extending through the accumulator member.

The two cylinders or tubular containers are connected at their top by a pipe 32, as shown in Figs. 10 and 12, and at their bottom by a pipe 33, this pipe having connected therewith a supply pipe 34 by which liquid is delivered to and from the accumulator.

A plunger 36 operates in the power cylinder 20 and reciprocates toward and from the platen 15. To this plunger is attached an arm 37 having at its free end an eye which fits freely around a rod 38 slideably mounted on a bracket 39 and having suitable stop collars thereon adapted to be engaged by the arm 37. This rod 38 is connected with the control valve, and when shifted by engagement of the arm 37 with the collars, serves to operate the valve so as to limit the movement of the plunger in either direction. This is the usual limit stop arrangement and requires no detailed description.

Two manual control levers 40 and 41 are provided, one at the front of the press adjacent the platen, and the other at the side, as clearly shown in Figs. 1 and 2. These operating levers are connected together in the following manner. The lever 40 is secured to a rock shaft 42 which extends through the plates 6 and 7, and also through the tunnel 31 and into the passageway formed by the angle iron 30, as shown in Fig. 15. The rock shaft 42 carries a crank arm 43 at its end, and this is pivotally connected with an up-and-down rod 44 which extends up through the vertical passageway to a four-way control valve, such valve being indicated at 47 in Fig. 14. The lever 41 is pivotally mounted in an opening in the side plate 3 and has a bifurcated end 45 which straddles

and is connected with the rod 44. Thus, by rocking either the lever 40 or the lever 41, the rod 44 may be reciprocated and the valve shifted as desired.

In Fig. 14, I have illustrated a simple hydraulic arrangement which may be employed in connection with my improved press, although such an arrangement constitutes no part of the present invention, and is illustrated by way of example only. In this figure, the power cylinder is indicated at 20, and a pipe 46 communicates with the upper end and a pipe 49 with the lower end. These two pipes are controlled by the four-way valve 47 above referred to. From this valve extends a pipe 48 to the liquid reservoir 35, and from the valve also extends another pipe comprising the sections 50 and 51, which connects with the delivery side of a pump 52, the intake side of the pump being connected with a pipe 53 also extending into the liquid reservoir 35.

Interposed in the pipe line 50, 51 is an ordinary check valve 56 and an unloading valve 54, a by-pass or remote control pipe 57 extending around the check valve 56 as shown. A so-called sequence check valve 58 is connected at one side to the pipe line 50 and at the other side to the supply pipe 34 which delivers into the accumulator 24.

When in neutral position, the four-way valve 47 blocks the pressure line from pump and accumulator. When the pump is started, the pressure builds up rapidly until it reaches the predetermined setting of the sequence check valve 58, when this valve opens and allows the pump to store liquid in the accumulator. As the level in the accumulator rises, the contained air is compressed and the pressure increases until the setting of the unloading valve 54 is reached, whereupon this valve opens and the liquid is by-passed from the pipe 51 back through the pipe 55 to the tank or reservoir 35. The check valve 56 prevents the liquid stored in the accumulator 24 from flowing back through this by-pass also.

When one of the levers 40 or 41 is shifted, say, to the "down" position, the liquid in the accumulator flows freely through the sequence check valve and pipe line 46 to the top of the power cylinder. In addition, the moment there is a pressure drop in the remote control line 57 which causes the unloading valve 54 to close, thus forcing liquid from the pump out through the line 50, thus adding this volume of liquid to that from the accumulator.

As the plunger 36 moves downward, a point will usually be reached where the pressure in the accumulator will drop to a point less than that required to cause the plunger to perform the desired work. At this point, the sequence check valve will close, thus cutting off the accumulator and allowing the pump to furnish the necessary pressure to finish the stroke. Thereupon, the pressure in line 50, generated by the pump, continues to rise until the sequence valve opens again, allowing the pump to refill the accumulator.

It will be understood that all of the mechanism and apparatus shown in Fig. 14 is contained within the space between the two side plates 2 and 3 of the press frame. The valves 47, 54, 56 and 58 will ordinarily be contained in the chamber or compartment above the floor 18. For the sake of clearness and also because various different arrangements of valves and piping may be employed, I have not attempted to illustrate this mechanism in the other views of the drawing. In Fig. 16, however, I have shown in dotted lines

the pipes 49, 51 and 53, and the pump 52, illustrating the same as being driven by an electric motor 59. Also the pipe 46 has been shown in Figs. 1, 2 and 3.

5 What I claim is:

1. A hydraulic press frame of the gap type comprising a hollow structure composed of side and edge plates welded together along their meeting edges, and a platen resting on a portion of said side plates adjacent the gap, said platen projecting laterally beyond said side plates and the projecting portions being supported by auxiliary vertical plates rigidly connected with said side plates by welding.
- 10 2. A hydraulic press frame of the gap type comprising a hollow structure composed of side and edge plates welded together along their meeting edges, a platen resting on a portion of said side plates adjacent the gap, said platen projecting laterally beyond said side plates and the projecting portions being supported by auxiliary vertical plates, and a vertical front plate bridging said side and auxiliary plates and welded thereto.
- 15 3. A hydraulic press frame substantially rectangular in horizontal section and comprising side and bottom plates, and one edge plate united along their edges by welding, said side and edge plates providing three walls of a chamber constituting a liquid reservoir, and a vertical accumulator structure disposed between said side plates at a point spaced from said edge plate, said chamber having a fourth wall formed at least in part by said accumulator structure.
- 20 4. A hydraulic press frame comprising spaced side plates, and an accumulator consisting of a vertically extending, closed, hollow structure interposed between said side plates and anchored thereto by welding.
- 25 5. A hydraulic press frame comprising spaced side plates, and an accumulator structure composed of one or more vertical cylinders located between said side plates and anchored thereto by welding.
- 30 6. A hydraulic press frame comprising side, edge and bottom plates forming a chamber constituting a liquid reservoir, and an accumulator structure including one or more vertical cylinders disposed between and anchored to said side plates by welding, said accumulator structure serving as one wall of said liquid reservoir.
- 35 7. A hydraulic press frame comprising side, edge and bottom plates forming a chamber constituting a liquid reservoir, an accumulator structure also contained between said side walls, a pump for delivering liquid from said reservoir to said accumulator, and a chamber between said side walls and above said liquid reservoir in which said pump is mounted.
- 40 8. A hydraulic press frame comprising spaced side plates, a vertical accumulator structure enclosed between said side plates and welded thereto, a power cylinder also located between said side plates laterally of said accumulator structure, and vertical brace plates extending between said accumulator structure and power cylinder and tying them together.
- 45 9. A hydraulic press frame of the gap type comprising spaced side plates extending beneath the gap, a platen supported on said plates, a transverse vertical plate extending between said side plates adjacent the platen and tying them together, an accumulator structure mounted between said side plates and anchored thereto, and
- 50 75

vertical brace plates, connecting said transverse plate with said accumulator structure.

10. A hydraulic press frame comprising side, edge and bottom plates forming a chamber constituting a liquid reservoir, a pump and control mechanism located within said frame above said reservoir, a vertical passageway extending up through said liquid reservoir to said control mechanism, an actuating rod extending through said passageway, and a control lever mounted on said frame and operatively connected with said rod.

11. A hollow press frame comprising spaced side plates, a plurality of accumulator cylinders disposed between said plates and tied thereto and to each other by welding, control mechanism mounted in the upper part of said frame, a tunnel extending through one of said accumulator cylinders, and an operating rod passing through said tunnel and connected with said mechanism.

12. A hydraulic press frame comprising a base plate, a pair of spaced side plates secured to said base plate, and a pair of closed accumulator cylinders extending vertically from said base plate between said side plates and tied to each other and to said side plates by welding.

10

5

13. A hydraulic press frame comprising a pair of spaced side plates, and an accumulator unit consisting of a separately formed, closed, hollow structure disposed in and substantially filling the space between said side plates, and anchored thereto by welding.
